CONCEALED DOOR HINGE

Stanley W. Nicholson, Toledo, Ohio, assignor to
Detroit Harvester Company, Detroit, Mich., a
corporation of Michigan

Application February 11, 1938, Serial No. 189,991

7 Claims. (Cl. 16—164)

This invention relates to door hinges particularly adapted for use on vehicles but of much wider application and is particularly concerned with hinges of the so-called concealed type which are out of sight when the door is in closed position, thus distinguishing particularly from the so-called butt hinges which, when the door is closed, project outwardly and are objectionable and unsightly in appearance.

10 Numerous concealed hinges for automobile doors have heretofore been designed but none of them so far as I am aware has been entirely satisfactory. Among the objections to existing hinges of this type are the sizable expense of manufacture, the exceedingly complicated structure involving the use of links and slides, and the necessity for cutting out or removing substantial portions either of the door structure or the supporting frame.

20 This invention overcomes the above difficulties by producing a concealed door hinge which is exceedingly simple in construction, sturdy and reliable in operation, relatively inexpensive to manufacture and install without cutting or removing substantial areas of the door or frame. Contrary to the operation of many door hinges, the hinge in accordance with this invention does not impart such a strain on the frame as to distort it, thereby militating against the door becoming 30 sprung or otherwise distorted.

An object of this invention is therefore to produce a new and improved concealed door hinge which is simple in construction, reliable in operation, inexpensive to manufacture, convenient to 35 install and has the novel features of construction and operation hereinafter described.

For purposes of illustration but not of limitation, embodiments of the invention are shown on the accompanying drawings in which

40 Figure 1 is a side elevation of an automobile door showing the concealed hinges in dotted lines;

Figure 2 is a vertical end elevation showing the relative arrangement of the two hinges;

45 Figure 3 is an enlarged elevation of a portion of the door and its frame with a portion broken away to show a hinge member and the bearing socket members therefor;

Figure 4 is a side elevation of a hinge member;

50 Figure 5 is an end edge view of the hinge member, showing particularly the relative angular position of the connector arm with respect to the crank and stem portions;

Figure 6 is an enlarged transverse sectional view substantially on the line 6—6 of Figure 3;

Figure 7 is a vertical sectional elevation substantially on the line 7—7 of Figure 6;

Figure 8 is a fragmentary end elevation of the socket bearing member secured to the door;

Figure 9 is a vertical sectional elevation substantially on the line 9—9 of Figure 7;

Figure 10 is a transverse sectional view on the line 10—10 of Figure 7, diagrammatically illustrating the swinging movement accomplished by 10 the door;

Figure 11 is a side elevation of an automobile door showing an alternate form of concealed door hinge;

Figure 12 is a vertical end elevation showing the relative position of the hinge members; 15

Figure 13 is an enlarged fragmentary elevation of a portion of the door and frame broken away to show in sectional elevation the hinge structure;

Figure 14 is a side elevation of one of the hinge 20 members shown on Figures 11 to 13;

Figure 15 is an enlarged transverse sectional elevation on the line 15—15 of Figure 13;

Figure 16 is a vertical sectional view substantially on the line 16—16 of Figure 15; and 25

Figure 17 is a sectional view substantially on the line 17—17 of Figure 16 and diagrammatically illustrating the arc of swinging movement of the connector arm.

The illustrated embodiment of the invention 30

shown on Figures 1 to 10 comprises an automobile door 10 provided with the usual latch operating handle 11 and window glass 12, the door being mounted in the frame formed in the vehicle body 13 for swinging movements about a 35 substantially vertical axis to and from closed position. The vehicle body 13 has a vertically disposed panel or pillar 14 and ordinarily the hinges for connecting the door and body are connected respectively to the pillar 14 and adjacent portion 40 of the door in the form of a vertical panel or pillar 15 integral with the door, the body being recessed at 16 and an overlapping flange 17 covering the space between the door and the frame.

Two vertically spaced hinges 18 connect the 45 door to the body and enable the door to swing to and from closed position in the desired manner. As will hereinafter appear, these hinges do not have to be exactly in alignment with each other, and this is a distinct improvement over 50 the usual butt hinges whose axes must be in exact alignment for the door to swing properly. Within limitations, the hinges 18 can be disposed out of axial alignment without adversely affecting the swinging movement of the door. The 55

hinges 18 are identical in construction and each comprises a stem portion 19 which inclines upwardly and outwardly from the body pillar 14, a downwardly and outwardly inclined crank arm 20 which is integral with the upper end of the stem 19 and a connector arm 21 which is integral with the lower end of the crank arm 20 and extends outwardly therefrom. The stem portion or bearing arm 19 is rotatably mounted in an elongate bearing socket 22 formed in a bearing member 23 which is secured on the inside of the body pillar 14 by screws 24. The arm 19 is round in cross section and is adapted to rotate in the socket 22, the lower end bottoming against the lower end of the socket or if desired, a washer 34 disposed therein as illustrated in Figure 16. The crank arm 20 is disposed in the space between the body pillar 14 and door panel 15. The connector arm 21 is round and, as shown, inclines upwardly into a bearing socket 25 formed in a bearing member 26 which is secured to the inside of the door panel or pillar 15 by screws 27.

It will be observed that openings preferably oval in shape are formed in the pillars 14 and 15 to receive the arms 19 and 21 respectively. The socket 25 laterally is of a dimension to fit nicely the round connector arm 21 but in a vertical direction is elongate as shown on Figure 8. The upper and lower sides of the socket 25 taper downwardly to the lower end of the socket to substantially the circumference of the arm 21, thereby enabling the outer end portion of the arm 21 to have limited rocking movement in a vertical direction for a purpose which will hereinafter appear. The connector arm 21 is held in position by a washer 28 on the outer end thereof which engages the outer side of the bearing member 26.

As shown, the stem portion or bearing arm 19 is inclined at about 30° from the vertical and the depending crank arm 20 forms with the arm 19 an angle of the order of 39°. The connector arm 21 forms with the crank arm 20 an angle of approximately 30°. It is important that the connector arm 21 be out of parallel with respect to the arm 19 and although an angle of 80° between the crank arm 20 and connector arm 21 operates satisfactorily, and is desirable because it provides a hook support or mounting for the door and takes away the load or thrust upon the washer 28, that angle can be varied within certain limits. I found that the more closely the connector arm 21 approaches the crank arm 20, the more restricted will be the door opening movement.

As above mentioned, however, it is important that the arms 19 and 21 be non-parallel with respect to each other because in their parallel relation, swinging movement of the door to open it in the desired manner cannot be effected. With the connector arm 21 disposed at substantially right angles with respect to the crank arm 20, a door swinging movement of substantially 90° can be obtained but ordinarily in the case of vehicle doors, an opening movement of between 70° and 80° is considered adequate and with the connector arm 21 disposed at an angle of approximately 80° relative to the crank arm, a door opening movement of approximately 72° is obtainable. It is not imperative that the stem portion or bearing arm 19 be disposed at an angle of 30° with respect to the vertical and that should not be considered a critical angle but by experience, the bearing arm disposed at a 30° angle has been found to be entirely satisfactory for effecting the

desired door swinging movement. It should also be mentioned that the relative lengths of the arms and the angles which they form within the limits above defined can be varied but experiments have established that a hinge as shown and above described operates entirely satisfactory to effect the desired door swinging movement. 5

As shown on Figure 5, the arms 19 and 20 are in alignment with each other but the connector arm 21 is inclined laterally. This inclination is 10 desirable only because it lessens the movement of the arm 21 within the socket 25. The amount of inclination of the arm 21 is limited by its nearness to the upholstery. If the upholstery did not interfere, it would be desirable to increase the 15 inclination of this arm. This is most clearly illustrated on Figure 6 which shows that the socket bearing 26 for the arm 21 terminates close to the inside of the door. As the door swings to and from closed position, a slight vertical rocking movement of the arm 21 in the socket 25 takes place but such movement is diminished when the arm 21 is laterally inclined as above described.

In the movement of the door to and from closed 25 position, it should be understood that the stem or bearing arm 19 rotates in its socket bearing 23 and also the connector arm 21 rotates in its socket bearing 26 as well as having a slight rocking movement therein as above indicated. During this movement, the crank arm 20 swings through an arc of approximately 60° but the door is enabled to swing through approximately an arc of 72° in the form shown. This additional 12° of door swinging movement is obtained because 35 of the angularity of the parts and the compensating action of one part with respect to another.

The form of the invention shown in Figures 11 to 17 is similar to the hinge above described, and has a stem or bearing arm 19a which is disposed 40 at an approximately 30° angle with respect to the vertical and is rotatably socketed in a bearing member 23a secured by screws 24a to the body pillar 14a of the vehicle body 13a. The crank arm 20a which is integral with the upper end 45 of the arm 19a extends downwardly similar to the arm 20 but, as particularly shown in Figure 14, widens out materially at its lower end to provide laterally spaced integral bearing bosses 29. In the space between the bosses 29 is an annular 50 bearing sleeve 30 the bore of which aligns with the bores of the bosses 29. A pin 31 extends through the bores of the bearing bosses 29 and sleeve 30, and about which the sleeve 30 is adapted to rock. Integral with the sleeve 30 is a connector 55 arm 32 which is in screw-threaded engagement with the socket bearing member 33 secured by screws 34 to the pillar 35 of the door 10a. It will be observed that the connector arm 32 is disposed at substantially right angles to the crank arm 20a 60 which, as above pointed out, enables the door to swing through approximately an arc of 90°. The connector arm 32 rotates in the bearing member 33 during its swinging movement to and from closed position, the screw threads causing it to 65 move slightly in and out of the bearing 33 but these threads also function to hold the connector arm against undesirable axial movement. Portions of the door and frame pillars are suitably embossed inwardly to accommodate the 70 parts.

Attention is called to Figure 17 which diagrammatically illustrates the manner in which the connector arm 32 swings during the door-opening movement. It will be observed that it swings 75

5 relatively to the crank arm 20a and also rotates relative to the bearing 33. Since the angularity of the parts and the relative lengths of the arms is similar to that hereinbefore discussed, further 10 description is not considered necessary.

From the above description, it will be apparent that I have produced an exceedingly simple hinge which in one instance comprises merely a one-piece round bar forging which can be produced 15 for an extremely low cost and because of its inherent simplicity of construction can be easily installed and in operation there is virtually nothing to get out of order, adjustment or alignment. The socket bearing members manifestly 20 can be inexpensively manufactured and installed and adequately support the hinge parts. Thus, a hinge of this character fully satisfies the objects primarily enumerated and satisfactorily overcomes objections and difficulties heretofore experienced in connection with concealed door 25 hinges.

It is to be understood that the invention is not limited to hinges for vehicle bodies but can be used in many other places and it will be also understood that changes in details of construction and operation may be effected without departing from the spirit of the invention especially as defined in the appended claims.

What I claim is:

30 1. A hinge for connecting door and frame parts comprising a stem portion obliquely socketed in one part for rotation therein and extending therefrom into a space provided between the edges of said parts when the door is closed, a 35 crank portion rigid with said stem portion and forming therewith an acute angle, and a connector portion extending substantially horizontally from said crank portion at a level below the upper end of the stem portion and rotatably 40 socketed in the other part.

2. A hinge for connecting door and frame parts comprising a stem portion obliquely socketed in one part for rotation therein and extending therefrom into a space provided between the edges of said parts when the door is closed, a 45 crank portion rigid with said stem portion and forming therewith an acute angle, and a connector portion extending substantially horizontally and away from said crank portion and rotatably 50 socketed in the other part, the axes of said stem and connector portions being disposed at an angle and out of parallel relationship to each other.

3. A hinge for connecting door and frame parts comprising a stem portion obliquely socketed in one part for rotation therein, a crank portion rigid with said stem portion and forming therewith an acute angle, and a connector portion pivoted to said crank portion and extending substantially horizontally into rotatable socketed engagement with the other part.

4. A hinge for connecting door and frame parts comprising a socket bearing connected to one 10 part inclining longitudinally relative thereto, a rod-like stem portion having a nice rotatable fit in said socket bearing, a crank portion with its upper end rigid with the outer end of said stem portion and forming therewith an acute angle, 15 a socket bearing in the other part, and a rod-like connector portion extending substantially horizontally from the lower end of said crank portion and in screw-threaded engagement with said last socket bearing.

5. A hinge for connecting door and frame parts comprising a stem portion, a crank portion integral with one end of the stem portion and forming an acute angle therewith, and a connector portion hinged for movements to and from said 25 crank portion and disposed to provide an angle of the order of 90° relative to said crank portion when the door is closed, and screw-threads on said connector portion.

6. A hinge for connecting door and frame parts 30 comprising a rod-like stem portion obliquely socketed in one part for rotation therein and extending therefrom into a space provided between the edges of said parts when the door is closed, a crank portion with its upper end rigid with the 35 outer end of said stem portion and forming therewith an acute angle, and a rod-like connector portion pivoted to said crank portion at its lower end and extending substantially horizontally into rotatable socketed screw-threaded engagement with a socket bearing on the other part.

7. A hinge for connecting door and frame parts comprising a stem portion obliquely socketed in one part for rotation therein and extending therefrom into a space provided between the 45 edges of said parts when the door is closed, a crank portion integral with said stem portion and forming therewith an acute angle, and a connector portion pivoted to said crank portion and extending substantially horizontally into rotatable engagement with the other part.

STANLEY W. NICHOLSON.
